 Ind., a corporation of Indiana

Original application February 25, 1931, Serial No.
 518,281. Divided and this application March
 30, 1932, Serial No. 602,007

15 Claims. (Cl. 201—55)

This invention relates to circuit controllers, and more particularly to circuit controllers for use in volume control units for radio equipment and the like.

5 In the preferred embodiment of my invention I have disclosed a circuit controller comprising a wound wire resistance concentrically mounted in a suitable casing, and adapted to be engaged by a suitable contact or shoe carried by a rotatable actuating arm.

As discussed more fully in my copending application Serial No. 518,281, filed February 25, 1931, this application being a division thereof, the controller of the present invention possesses 15 distinct advantages over those of the prior art. While I have provided a wound wire resistance, it is to be understood that any other suitable resistance may be used, and the invention is not to be limited to controllers having only wound 20 wire types of resistances.

One feature of the present invention resides in the compact assembly of the resistance within the casing. The resistance is formed by winding a wire upon a substantially elongated rectangular 25 strip of insulating material, which may be fiber, or a combination of fiber and a phenolic compound, the strip preferably being laminated. The resistance is then formed into a substantially cylindrical configuration, and is provided with terminal members secured over and short circuited on the end turns of the coil. These terminal members are extended outwardly through suitable openings formed in the cup-shaped casing and the resistance coil is mounted within the 30 casing with its ends in abutting engagement.

In connection with this feature, the contact strip is held in place within the casing by expanding it into the shell and utilizing its compressive strength for maintaining it in substantially cylindrical form and concentric position 40 about the rotatable rheostat shaft.

Also, the manner of bringing the terminals out from the interior of the shell without providing an opening through which dust or foreign matter 45 might enter the interior of the shell, assures that the resistance strip will be disposed within the shell in substantially a dust-proof casing. Associated with this feature is the novel manner of making electrical contact between the terminals and the wire resistor.

Another feature of the present invention is the provision of a dust-proof casing, a part of which may be in the form of a cover or a cooperating shell engaging the cup-shaped shell, and com-

pletely enclosing the operating parts of the controller.

Numerous other advantages, such as the manner of assembly and the construction of individual parts of the controller, will be more apparent 5 from the following detailed description, which, taken in connection with the accompanying drawings, will disclose to those skilled in the art the particular construction and operation of a preferred embodiment of the circuit controller 10 of the present invention.

In the drawings:

Figure 1 is an elevational view of the controller as assembled;

Figure 2 is a sectional view taken substantially 15 on the line 2—2 of Figure 1, showing the interior of the controller shell, the controller being provided with a knob for actuating the same;

Figure 3 is an end elevational view of the controller with the cover removed;

Figures 4 and 5 are fragmentary detail views 20 of the contacting means and the terminal members of the controller, showing the contacting shoe in two positions relative to the terminal end of the resistance strip;

Figure 6 is a fragmentary sectional view taken substantially on the line 6—6 of Figure 3;

Figure 7 is a partial sectional view, taken substantially on the line 7—7 of Figure 3;

Figure 8 is a perspective detail view of the 30 center terminal of the controller; and

Figure 9 is a perspective detail view of one of the terminals connected to each end of the resistance strip, and

Figure 10 is a fragmentary, sectional view of 35 a detail.

Referring now in more detail to the drawings, and particularly to Figures 1 and 2, I have disclosed a cylindrical cup-shaped shell member 1 forming part of a closed housing. The shell has 40 a cylindrical wall 2 and a substantially flat end wall 3. The end wall 3 has a bearing sleeve 4, which may be formed of brass, bronze or the like, and which is secured in an opening formed in the end wall 3 of the shell member. 45

The sleeve is substantially concentric with the cylindrical wall 2 of the shell or casing 1, and serves as a bearing for the actuator shaft 5, and also serves to support the rheostat or controller on a panel 6, which may be a thin metallic plate 50 or the like. The outwardly projecting portion of the sleeve 4 is threaded as shown at 7, and receives a clamping nut 8 for securing the controller to the panel 6, there being a washer 9 interposed between the nut and the panel. 55

The opening in the end wall 3 of the shell member preferably is provided with radial projections, and the sleeve is expanded into engagement therewith by endwise pressure upon the shoulder 5 10. A suitable knob or actuating member 12, formed of bakelite or the like, is secured by means of a set screw 13 to the outer end of the shaft 5, and is non-rotatably engaged therewith for the purpose of actuating the shaft. The shaft 5 is held against endwise movement within the sleeve 4 by means of a flat split ring 14, which is shrunk or deformed into the annular groove 15 in the shaft 5, the ring 14 bearing against the end of the threaded portion 7 of the sleeve.

15 At the opposite end of the shaft 5 an actuator or arm 16, in the form of a thin plate of brass or the like, is secured about the reduced end 17 of the shaft, as by means of the riveted head 18 thereof, which may be spun over or suitably formed to hold the actuator arm 16 in firm non-rotative engagement therewith. The hole in the actuator 16 is provided with keying projections extending radially inwardly, and when the reduced end of the shaft 5 is riveted thereover, the metal is expanded into keying engagement with these projections. The actuator is thus held between the shoulder of the shaft and the riveted head in non-rotative engagement. The arm or actuator 16 also serves to limit endwise movement 25 of the shaft outwardly of the casing, thus cooperating with the split ring 14 for holding the shaft in operative position within the casing.

30 The housing or shell member 1 contains a cylindrical resistor 18, which comprises, in a preferred embodiment, a strip of laminated phenolic compound 19 of a special composition rendering the same sufficiently flexible to permit bending, when heated, of the relatively short length which is thus formed into cylindrical shape. A resistance wire, preferably of great length and of very small diameter is wound upon the strip 19. For example, the strip 19 may be wound with wire .002 of an inch in diameter with but .0001 of an inch space between the turns thereof. Such a resistor will thus have 466 turns of wire per lineal inch along the strip, providing a very fine adjustment of resistance for the controller. The particular diameter of the wire, and the number of turns per inch, is, of course optional. The ends 45 of the strip 19 are notched, as shown at 20 in Figure 2, to permit the passage of a rivet 22 therethrough, as will be described in detail later.

50 Between the resistor 18 and the flanged wall 2 of the shell is inserted an insulating strip of fiber 23, which, after suitably dehydrating, is cut to a length such that it fits snugly into the interior of the cylindrical wall when the ends are brought into registry by expanding the same under pressure within the shell or housing. As shown in Figure 3, the abutting ends of the insulating strip 23 are indicated at 24, and are disposed diametrically opposite the abutting ends, indicated at 25, of the resistance strip 19.

55 The liner 23 is provided with openings having the form of slits, such as the slit 26 shown in Figure 6, and the shell is provided with a pair of openings or apertures 27 which are disposed at each side of the abutting ends 25 of the resistor. The slits 26 of the liner 23 are so disposed as to register with the central parts of the apertures 27, and through these slits and apertures are thrust the lead portions or terminals 28 of the terminal members 29. The terminal members 29 are formed of springy sheet metal with a base 70 or foot portion 30 extending at substantially right

angles to the terminal or lead portion 28. This base portion 30 is cut or notched at 32 to provide clearance around the rivet 22, which rivet is grounded on the shell 1, as shown in Figure 7. At the juncture of the base 30 and the terminal portion 28 of the terminals 29 I provide a corrugation or web 33 to strengthen the connection between the terminal portion and the base portion. This inhibits breakage by bending at the corner.

10 These terminal portions being thin flat members project through the slits 26 to the exterior of the housing. The liner 23 forms a shield for the openings 27 as the slits grip the lead portion 28 closely, preventing the entry of foreign matter 15 such as dust, dirt and the like to the interior of the controller. The members 29 are made as left hand members and right hand members, as will be apparent from Figures 3 and 7, but otherwise are identical in form. The terminal portions 28 thereof are adapted to receive connecting wires, and for this purpose are provided with eyes or openings 34 at their outer ends, and also have dove-tailed notches 35 adjacent the eyes or openings 34. The dove-tailed notches 35 provide a portion of reduced diameter around which still other wires may be connected and thereby held preparatory to being soldered to the terminal 28. The shape of the corners of the dove-tailed notches tends to catch the turns of wire 30 and hold the same securely.

A ring or washer 36 of insulation such as fiber, or the like, is disposed between the end wall 3 of the cup 1 and the resistor 18, as shown in Figures 2, 6, and 7. In assembling the parts within the 35 cup or shell member 1, the washer 36 is first introduced inside the cup, then the liner 23, which has been dehydrated to shrink the same, is introduced into the cup and the opening 37 at the central part of the liner is brought into register 40 with an opening in the cylindrical wall 2 as shown in Figure 2, and the liner is then expanded until its abutting ends are aligned as shown at 24 in Figure 3. Thereupon the terminal members 29 and leads 28 are thrust through the slits 26 in 45 the liner and the bases, which are lefts and rights, have their notches 32 extended toward each other and rest against the inner cylindrical wall of the liner. The resistor, which is coiled up in cylindrical form, is then introduced into the shell and 50 it is expanded with considerable force until the ends which are aligned with the opening 37 in the liner and the opening in the shell 1, abut into abutting relation. The round notches 20 then provide an opening through which the shank of 55 the rivet 22 extends.

55 It will be observed that the base portions 30 of the terminal members 29 (see Fig. 9) are flat and not cylindrical. Therefore, when a resistor is expanded to bring the ends into register it is 60 first necessary to spring the flat bases 30 into the form of arcs so that the base portions 30 conform to the curvature of the liner 23 and the resiliency of these parts causes them always to thrust inwardly against the resistor, and particularly against the turns of the winding at the ends of the resistor which they engage. If desired, a small piece of soft metal foil may be inserted between the base portions 30 and the windings which are to be engaged by the terminals to insure good contact with the predetermined part of the resistor. These pieces of foil may extend beyond the end of the winding directly under the pressure of rivet 22 exerted through the head 38 and washer 39. Such a 70 75

piece of metal foil is particularly desirable when it is desired to short circuit a portion of the winding beyond the terminal. This is especially true in rheostats or circuit controllers having a switch in combination therewith, as disclosed in my copending application, Serial No. 602,006, filed March 30, 1932, so that enough of the winding is short circuited to provide zero resistance after the switch closes the circuit.

The rivet 22 has a cylindrical shank which extends through the aligned openings of the resistor, the insulating strip, and the cylindrical shell member. Obviously, the shank of the rivet 37' might be tapered adjacent the head 38' for further exerting a spreading force upon the ends of the resistor strip 19 as shown in Fig. 10. The rivet has a spring washer 38 under the head 38 for spreading the pressure of the rivet, this washer being sprung into an arcuate form when the rivet is drawn up. The abutting ends of the resistor supporting strip 19, Figures 2 to 5, inclusive, are thereby held in register both radially and axially. A central or grounded terminal 40 is clamped to the outside of the center cylindrical wall by the beaded or riveted end of the rivet 22. The terminal member 40, as shown in detail in Figure 8, has a terminal portion 42 substantially like the portion 28 of the terminal member 28. The base or body portion 43 has a hole 44 therethrough which receives the rivet 22, and is provided with a small projection 45 entering a corresponding opening 46 in the cover member, as shown in Figure 1, to secure the member 40 against rotation about the axis of the rivet so that the terminal portions 28, 28 and 42 are all in substantially the same plane, as is apparent from Figure 1. The end of the casing is closed by a metallic cap 47 which has a flange embracing the outside of the cylindrical wall 2.

The outer edge of the cylindrical wall 2 is rounded on both inside and outside corners to facilitate the application of the cap to the outside thereof, and also to facilitate the insertion of the liner 23 on the inside of the shell. This rounded edge also prevents the cutting of the wire windings carried by the strip 18 during assembly thereof within the shell, which might occur if the inner edge of wall 2 were not rounded.

The actuator or arm 16 is provided with two hooks or projections 48 spaced apart angularly with respect to the axis of the shaft by a relatively wide angle. The actuator 16 carries the shoe member 49, this shoe member having a pair of runners 50, which are formed integrally of a piece of thin sheet metal, preferably of a special composition for insuring good contact with the resistance wire. The particular formation of the contactor shoe is described more in detail in my above mentioned copending application, Serial No. 518,281, filed February 25, 1931, of which application the instant application is a division. Suffice to say that the shoe 49 is provided with yoke-shaped ends 51 which engage about the hooks 48 for securing the shoe to the actuator arm, the shoe being forced into contact by means of the pressure spring 52 biased therebetween. It will be noted that the contactor and the actuator arms have relatively telescoping engagement, and, as shown particularly in Figures 4 and 5, the actuator arm is adapted to lead the contact shoe in either direction of movement, the shoe being pulled at a point spaced away from the actual point of engagement. The purpose of this particular construction is more fully described in my copending application.

Two stop arms 54 on each side of the spring member 52 and integral with the actuator arm 16 are adapted to engage the head 38 of the rivet 22 for limiting the motion of the arm, and consequently limiting the motion of the contactor shoe. These stop arms or projecting lug portions extend through the yokes of the shoe 49, and the shoe is free to have universal movement thereabout. The arm 16 is also provided with an extending tongue portion 55 having an opening 56 therein, this opening being adapted to receive an operating pin when the circuit controller is mounted in conjunction with the circuit opening and closing switch. The arm 16 is also provided with a pair of diametrically extending slotted 15 tongues 57, which are adapted to receive a coupling member when two or more circuit controllers are mounted in tandem arrangement, as fully described in my above mentioned copending application.

To insure smooth operation mechanically and electrically within the circuit controller, the housing is completely closed to exclude dust and foreign particles, and in addition the resistor strip and the liner and all insulating parts within the shell are covered with a neutral oil which forms a film upon the metallic contacting parts. The oil film also surrounds the insulating strip and winding strip, thus preventing them from undergoing dimensional changes due to changes in their moisture contents, since absorption of moisture or loss of moisture is greatly retarded.

In the assembly, in order to insure tightness of the resistor in the shell, I prefer to dehydrate the strip 23 before the same is inserted in the shell. 35 This dehydration contracts the same materially. After the rheostat is assembled the fiber liner is permitted to resume its normal moisture content, whereupon it expands and grips the resistor firmly. The oil is then introduced for the purposes above described.

While I have shown the terminals such as 28, extending out through the cylindrical wall 2, it is to be understood that I do not wish to limit the invention to that manner of taking out the 45 terminals. A fiber end liner or washer similar to washer 36 may be disposed within the open end of the shell and the terminal portions may be extended through corresponding slits in such washer and corresponding slots or apertures in 50 the cap or cover member 47. Or, if the mounting permits, the taking out of the terminals may be accomplished through the end wall 3. The employment of the fiber for sealing the openings or apertures through which the terminals 55 are projected is advantageous in preserving a complete closure. The soaking of the fiber insulation in oil assists, also, in excluding foreign particles such as dust and the like. The shaft 5 fits in the sleeve 4 with a very close fit and the 60 dimensions are held relatively close for end play, so that there is practically no opportunity for foreign particles to enter along the shaft.

The resistor 18 may be made up in a variety 65 of forms and to secure various effects, as above pointed out, without departing from the scope of the present invention. I have described this resistor as comprising a very large number of turns of fine wire wound about the strip of insulation 19. Preferably bare wire is employed, as with my method of making contact, bare wire with very little space between turns is entirely feasible, and there is not the difficulty of removing the enamel or other insulation which is the 70 75

case in rheostats where enamel wire or the like is employed.

I may form grooves on the edge of the strip and carry the bare wire in such grooves which 5 may be, relative to the diameter of the wire, quite deep. The wire turns along the central part of the flat side of the strip may be tied in place by depositing a suitable cement in a line along the center of each side of the long strip, this being applied after the winding of the wire upon 10 the strip and upon setting, or hardening, it forms a definite tie between the central parts of the coils and the side of the strip, which serves to anchor the turns against any shifting by the 15 contactor. The bending of the strip does not cause the cement to crack or split from between the adjacent coils.

The wire may be wound upon a smooth edged strip 19. Normally I prepare the strip 19 before winding by carefully rounding the edges and 20 truing the edges so as to assist in the accurate placing of the individual turns of the wire. It is desirable to cause the wire to be placed accurately and uniformly.

25 The wire which is wound upon the strip does not need to be the same throughout; there may be different sizes of wire wound upon the same strip, as, for example, the resistance strip may be wound with relatively coarse wire at a relatively coarse pitch adjacent the zero side of the resistance, and may be changed into relatively fine wire with a relatively fine pitch as the resistance nears the opposite end of the strip.

30 Other obvious changes may be made in the details of my circuit controller without departing from the scope and spirit of the invention, and I do not intend to be limited to the exact embodiment shown and described, but only in so far as defined by the appended claims.

35 I claim:

1. In combination, a substantially cylindrical cup member forming a housing, the cup member having openings through the cylindrical wall, a liner of insulation closely fitting the inner cylindrical wall of the cup member, said liner having openings in alignment with the openings in the shell, terminal members having flat base portions and thin outwardly extending lead portions, the lead portions being thrust through said 45 openings, a cylindrical resistor comprising a flat strip of insulation having a wire winding thereon brought to cylindrical form with the ends thereof abutting under compression, the ends of the wire winding engaging the base portions of the terminal members to secure electrical contact therewith.

50 2. In combination, a substantially cylindrical cup member forming a housing, the cup member having openings through the cylindrical wall, a liner of insulation closely fitting the inner cylindrical wall of the cup member, said liner having openings in alignment with the openings in the shell, terminal members having flat base portions and thin outwardly extending lead portions, the lead portions being thrust through said 55 openings, a cylindrical resistor comprising a flat strip of insulation having a wire winding thereon brought to cylindrical form with the ends thereof abutting under compression, the ends of the wire winding engaging the base portions of the terminal members to secure electrical contact therewith, and pads of soft metal disposed between the foot portions of the terminal members and the winding to form exten-

sive contact between the winding and the terminal members.

3. In a device of the class described, a metallic housing comprising a cylindrical cup member having a bearing sleeve coaxial with the cylindrical wall thereof, a liner of insulation closely fitting the interior of the cup member, said cup member having openings through a wall thereof, terminal members of sheet metal comprising base portions and outwardly extending lead portions, 1 said liner having openings in alignment with the openings in the cup member and the lead portions being thrust through said liner openings, a resistor comprising a flat strip of insulation having a resistance wire coiled thereupon to 1 points adjacent the ends of the strip, the ends of the strip being brought into abutting relation under compression between said terminal members, the base portions of the terminal members being brought into electrical contact with the 2 ends of the resistance winding by the radial outward thrust of the strip, and a pin extending through the strip at the ends thereof and through the cup member, said pin having a head for holding the abutting ends of the strip in alignment. 2

4. The method of mounting a resistor in a shell which comprises forming a cylindrical cup-shaped shell, disposing a compressible lining strip of insulation on the cylindrical inside surface of the shell, forming a wire wound strip of insulation 3 to a length slightly in excess of the inner periphery of the lining, disposing the strip within the lining, and extending the strip to bring the abutting ends thereof into register under compression. 3

5. In combination, a shell having a cylindrical wall, a liner of insulating fiber on the inside of the cylindrical wall, a resistor comprising a wire-wound strip of insulation, and terminals having 4 portions projecting from said shell and flat metal inserts disposed on the inner wall of the fiber liner and extending from said projecting portions circumferentially of said shell between said liner and said resistor, said resistor being of a length slightly greater than the normal internal 4 perimeter of the liner so that when the ends thereof are brought into abutting engagement a relatively great outward radial thrust will be created holding the resistor in the shell and providing permanent contact between the winding 5 and the metal inserts.

6. In combination, a housing having a cylindrical wall, openings in the wall, a liner of insulating material inside of the cylindrical wall, said liner having openings in register with the 6 said first-named openings, a resistor comprising a flat strip of insulation having a wire winding thereupon, the ends of the strip being free of the winding, said ends having registering notches, the strip being bent to approximately cylindrical 6 form and the ends thereof brought into register under compression, terminal members having base portions lying between the liner and the ends of the resistor and engaging the wire winding, 6 said terminal members having flat leads extending through the openings in the liner, and a headed pin extending through the registering notches of the resistor, through the liner and through the housing, the head of the pin holding the abutting ends of the resistor in alignment. 7

7. The combination with a housing having a cylindrical wall, a liner therein, the cylindrical wall and the liner having aligned openings, of a terminal member having a thin base portion dis-

posed on the inner surface of the liner and having a lead projecting through the openings, a resistor comprising a wire wound strip of insulation expanded into substantially cylindrical form with the ends thereof abutting in alinement under compression, and a headed pin extending through the liner and the cylindrical wall for holding said abutting ends in alinement.

8. In combination, a cylindrical shell member having a pair of apertures therein, a liner of insulation on the cylindrical wall thereof, said liner having apertures in register with the apertures in said shell member, registering openings in the liner and in the shell between said apertures, terminal members having thin base portions disposed on the inner wall of the liner and having flat leads projecting through the apertures, said base portions having notches adjacent the registering openings, a resistor strip expanded into engagement with the liner and having its ends abutting to hold the same under compression, said abutting ends being alined with said registering openings, and a headed pin extending through the alined ends and through the registering openings for holding the said ends in alinement and pressing the ends of the wire winding into engagement with the base portions of the terminal members.

9. In combination, a metallic supporting member, an insulating member in contact with the surface thereof, a terminal member having a flat base portion disposed upon said insulating member, a resistor comprising a strip of insulation having a wire winding thereupon extending to a point adjacent the end thereof overlying the insulating member, the base portion of the terminal member lying between the resistor and the insulating member and in contact with the end of the wire winding, and a rivet extending through the end of the strip of insulation, the insulating member and the metallic supporting member, said base member being formed to provide clearance between itself and the rivet.

10. In combination, a closed metallic housing having openings large enough to permit terminals to extend therethrough with clearance to avoid contact, a cylindrical wire wound resistor in the housing, a lining of insulation between the resistor and the adjacent walls of the housing, a shaft journaled in a wall of the housing substantially concentrically with the resistor, a movable contact shoe for engaging the windings of the resistor, said shaft having an actuating arm for the shoe, terminals projecting through the lining and the openings, said lining serving as a seal between the openings in the housing and the terminals, said terminals having contacting portions within the housing connected with the windings of the resistor.

11. In combination, a closed metallic housing having openings large enough to permit terminals to extend therethrough with clearance to avoid contact, a cylindrical wire wound resistor in the housing, a lining of insulation between the resistor and the adjacent walls of the housing, a

shaft journaled in a wall of the housing substantially concentrically with the resistor, a movable contact shoe for engaging the windings of the resistor, said shaft having an actuating arm for the shoe, terminals projecting through the lining and the openings, said lining serving as a seal between the openings in the housing and the terminals, said terminals having contacting portions within the housing connected with the windings of the resistor, said housing containing a body of lubricant for lubricating the shoe and the resistor. 5

12. In a rheostat, a housing, a cylindrical insulating liner engaging the inner surface of said housing, a concentric resistance strip spaced from 15 said housing by said insulating liner, said resistance strip having notched abutting ends, and means including a tapered conducting member extending through said housing for expanding said abutting ends to position said strip in said 20 housing.

13. In combination, a metallic rheostat housing having openings large enough to permit terminals to extend therethrough with clearance to avoid contact, a resistance element positioned 25 adjacent the inner wall of said housing, a flat lining of insulation, means securing said insulation in fixed position between the inner wall of the housing and said resistance element, terminals projecting through the lining and the openings, said lining fitting closely around said terminals to serve as a positioning means for the terminals and the sole means of insulation between the edges of the housing surrounding the openings and the terminals. 35

14. In combination, a metallic rheostat housing having openings large enough to permit terminals to extend therethrough with clearance to avoid contact, a resistance element positioned adjacent the inner wall of said housing, a strip 40 of insulation between the wall of the housing and said resistance element, means fixedly securing said strip in said housing, said strip having openings therethrough smaller than the metallic housing openings, terminals projecting through 45 the strip openings and the housing openings, said strip serving as a positioning means for the terminals to prevent electrical contact with the housing.

15. In a circuit controller, in combination, a metallic housing member having an opening therein, an insulating member lying against the inner wall of said housing member and having an opening registering with the opening in said housing member, a resistance element disposed 55 against said insulating member, a terminal having a substantially flat contact portion interposed between said resistance element and said insulating member and a lead portion extending through the said openings, and means securing 60 said resistance element in said housing member and clamping the contact portion of said terminal between said resistance element and said insulating member.

NEWTON C. SCHELLENGER. 65
